UNITED STATES PATENT OFFICE.

GOLDSBURY HARDEN POND, OF ASHBURNHAM, MASSACHUSETTS.

METHOD OF ELECTROLYTICALLY TREATING STRAW OR OTHER FIBROUS MATERIAL.

SPECIFICATION forming part of Letters Patent No. 616,139, dated December 20, 1898.

Application filed July 9, 1897. Serial No. 643,949. (No model.)

To all whom it may concern:

Be it known that I, GOLDSBURY HARDEN POND, a citizen of the United States, residing at Ashburnham, county of Worcester, State 5 of Massachusetts, have invented certain new and useful Improvements in Methods of Treating Straw or other Fibrous Material; and I do hereby declare the following to be a full, clear, and exact description of the invention, 10 such as will enable others skilled in the art to which it appertains to make and use the same.

My invention relates to an improved method of treating fibrous material for the manufacture of paper-pulp by electrolytically decomposing a solution of chlorid of sodium in the presence of calcium hydrate and then subjecting said material to the action of the resultant solution.

20 In electrolytically decomposing a solution of chlorid of sodium large quantities of chlorin are set free, which escape to the atmosphere and render it very disagreeable and dangerous to the workmen employed. This 25 objection is obviated by my invention, and such free chlorin, which has hitherto been wasted, is saved and utilized.

In the accompanying drawings, which show an apparatus for carrying my invention into 30 effect, Figure 1 is a longitudinal sectional view; Fig. 2, a horizontal section, and Fig. 3 a similar view of the inner shell or cylinder.

In the said drawings the reference-numeral 1 designates a cylindrical tank of wood or other 35 suitable material and of any suitable dimensions, and 2 an inner shell, which may also be made of wood, consisting of an open-ended cylinder concentric with said tank and formed at top and bottom with a number of circulation-ports 3. The space between said tank and shell forms a decomposition-chamber, and journaled centrally in the bottom of the tank is a vertical shaft 4, provided with a 40 pulley 5 and belt 6, by which it may be rotated from any suitable motor. Secured to the lower end of said shaft is a screw 7 for causing a circulation and mixing of the liquid or solution in the tank and shell. Located on the upper end of the tank is a 45 ducting-ring 8, connected by a conductor 9

with the positive pole of a dynamo or other source of electric supply. A similar ring 10 is located on the upper end of the shell, connected by conductor 12 with the negative pole of the dynamo. Numerals 13 and 14 55 designate electrodes, such as carbon, provided with hooks 15, which engage with said ring.

The operation is as follows: The tank is about half filled with milk of lime, made by 60 slaking common caustic lime with water and thinning down to the proper consistency. The tank is then filled up with a saturated solution of chlorid of sodium. A current of 65 electricity is now passed through the well-mixed solution, the screw being set in motion, so as to keep up a constant circulation of the solution in the tank and shell through the decomposing-chamber. The chlorid of sodium will now be decomposed, large quantities of 70 chlorin being set free, a part of which will combine with a part of the calcium hydrate, the resultant being a solution of hypochlorite of sodium, hypochlorite of calcium, and chlorid of sodium and uncombined calcium hydrate. The operation is then stopped and the calcium hydrate allowed to settle and the solution of hypochlorite of sodium, hypochlorite of calcium, and chlorid of sodium drawn 75 off into a tank containing straw or other material to be treated. It is then brought to the boiling-point and the straw subjected to its action until disintegration of the same is effected. The solution after having once been used is not thrown away, but is drawn 80 out into a tank provided therefor and allowed to settle. The solution is then pumped back into the decomposing-tank containing the uncombined calcium hydrate and again subjected to the electrical current, after having 85 been reinforced by the addition of more chlorid of sodium, and is thus worked over and over again.

Having thus fully described my invention, what I claim is--

The method herein described of treating straw and other fibrous material, which consists in electrolytically decomposing a solution of chlorid of sodium in the presence of calcium hydrate, in a suitable tank, the re- 90 95

sultant being a solution of hypochlorite of sodium, hypochlorite of calcium and chlorid of sodium, and uncombined calcium hydrate, then allowing the calcium hydrate to settle and drawing off the said solution, heating it and subjecting the straw to its action, then returning said solution to the decomposing-

tank containing the uncombined calcium hydrate, and reinforcing it with fresh chlorid of sodium and repeating the operation.

GOLDSBURY HARDEN POND.
